UNITED STATES PATENT OFFICE.

LAWRENCE LIPPI, OF NEW YORK, N. Y., ASSIGNOR TO R. W. AUBÉ & SON,
OF SAME PLACE.

DESIGN FOR MOLDING FOR PICTURE-FRAMES, &c.

SPECIFICATION forming part of Design No. 23,902, dated December 25, 1894.

Application filed November 26, 1894. Serial No. 530,054. Term of patent 3½ years.

To all whom it may concern:

Be it known that I, LAWRENCE LIPPI, a subject of the King of Italy, residing at New York, in the county of New York and State 5 of New York, have invented and produced a new and original Design for Picture-Frame Moldings and the Like, of which the following is a specification, reference being had to the accompanying drawings, forming part 10 thereof.

Figure 1 is a front view of a molding showing my design. Fig. 2, is a like view of a corner molding.

My design consists of an ornamentation 15 made up of leaves A, and the flowers B, both in relief, for a molding, which is suitable for picture frames and the like, to be arranged substantially as shown in the accompanying drawings.

The essential features of my design are the 20 ornamental leaves A, in relief occupying the full width of the base of the molding, with the flowers B, between the leaves as shown, said flowers having leaf petals. Between the large leaves A are the flowers B, composed of 25 flower petals united at their base. The base of the molding is ornamented as shown at D, in imitation of stipple work. The corner is formed of three leaves C united at their base and diverging from each other. 30

What I claim is—

The design for a molding for picture frames and the like substantially as herein shown and described.

LAWRENCE LIPPI.
